UNITED STATES PATENT OFFICE.

ELY R. WESTFALL, OF THE UNITED STATES ARMY.

PROCESS OF MAKING ANIMAL-MUZZLES.

1,256,625.

Specification of Letters Patent. Patented Feb. 19, 1918.

Application filed October 30, 1915, Serial No. 58,861. Renewed July 26, 1917. Serial No. 183,019.

To all whom it may concern:

Be it known that I, ELY R. WESTFALL, a citizen of the United States, residing at Camp Stotsenburg, in the county of Pampanga, Philippine Islands, have invented certain new and useful Improvements in Processes of Making Animal-Muzzles; and I do hereby declare the following to be a full, clear, and exact description of the invention, such as will enable others skilled in the art to which it appertains to make and use the same.

This invention relates to a process of forming nose baskets for horses, cattle, or other domestic animals; and the object of the invention is a comparatively simple process of intertwisting or weaving a plurality of wires for forming a strong, efficient, and durable animal muzzle.

With the foregoing and other objects in view this invention consists in the novel process of forming animal muzzles as will be hereinafter more fully described, illustrated in the accompanying drawings and claimed.

In describing the invention in detail reference will be had to the accompanying drawings wherein like characters designate like and corresponding parts throughout the several views, and in which:

Figure 1 is a side elevation of the improved muzzle,

Fig. 2 is a bottom plan view of the muzzle, showing parts broken away,

Fig. 3 is the first step employed in the weaving of the muzzle,

Fig. 4 is a view showing the second step employed in the weaving of the muzzle, and

Fig. 5 is a view showing an advance step in the process of weaving the muzzle.

In forming the body A of the basket, the eight wires indicated by the numerals 1, 2, 3, 4, 5, 6, 7, and 8, are employed which wires are initially bent to assume a U-shape, as shown in Fig. 3 of the drawings, and they are placed with their bight portions 10 facing each other and toward a universal or common center, indicated by the numeral 11. The legs of each of the U-shaped portions of wires 1, 2, 3 and 4, which are initially employed for forming the first step in the formation of the body A, are twisted together, a short distance outwardly from their bight portions 10, as is shown at 12, thereby forming four substantially

straight arms 13 which radiate from the common center 11. The legs of the wire 1 are twisted with the legs of the wires 2 and 3; the legs of the wire 2 are twisted with the legs of the wires 1 and 4; the legs of the wire 3 are twisted with the legs of the wires 1 and 4, and the legs of the wire 4 are twisted with the legs of the wires 2 and 3, as clearly shown in Fig. 4 of the drawings. The second set of four wires, namely, the wires 5, 6, 7 and 8, are then placed with their bight portions facing the common center 11, and they have portions of their legs twisted in the same manner as the legs of the wires 1, 2, 3 and 4 as clearly shown in Fig. 5 of the drawing, a short distance outwardly from their bight portions, as is shown at 14, forming substantially straight arms 15, which radiate from the common center 11. Each of the arms 15 is placed intermediate two of the arms 13, and the legs of the various U-shaped members cross at a point indicated at 17, forming eight substantially diamond-shaped portions 18 which radiate from the common center 11.

The legs of the U-shaped wires are twisted together at the outer points of the substantially diamond-shaped portions 18, as is shown at 19, and are bent inwardly, as is shown at 20, so that the facing legs of one of the initially employed U-shaped members may be twisted about the legs next thereto of the second employed U-shaped members, namely, the U-shaped wire members 5, 6, 7, and 8, forming straight tying sections 21. The sections of the legs of the U-shaped members are twisted three times, at the points 21, after which they are bent outwardly, as indicated at 22, and twisted again, as is shown at 23. The legs are twisted at 23, with portions of legs different from the ones which are twisted at 21. The foregoing last-mentioned step in the process of weaving the basket or muzzle, is repeated, until approximately the desired size of muzzle or basket is formed, which forms a plurality of polyhedral spaces 24 within and about the body of the basket. The legs of the wires are twisted in pairs, as is shown at 25, after the desired size of the body is formed, and they are coiled in opposite directions about the stay ring B, thereby forming a durable and comparatively rigid muzzle, which is constructed of intertwined wires, and which

has its upper open end or mouth supported by the stay wire B and an attaching strap C as indicated in Fig. 1.

The stay wire B may be bent circular, or 5 in any other desired shape, and it has its ends twisted about each other for forming a secure connection therebetween, as is shown at 26.

In reducing the invention to practice, certain minor features of construction, combination, and arrangement of parts may 10 necessitate alteration, to which the patentee is entitled, provided such alterations are comprehended within the scope of what is 15 claimed.

What is claimed is:—

1. The herein-described process of forming an animal muzzle including the bending of a plurality of strands of wire into 20 U-shape, placing the bight portions of substantially half the entire number of strands of wire facing each other and a common center, twisting portions of each of said strands of wire, in close proximity to the 25 bight portions, together with the corresponding portions of two of the other wires, placing the remaining half of the entire 30 number of wires radially about the common center, twisting portions of each of said last-named strands of wire together with the corresponding portions of two other of the last-mentioned strands so that the legs of the first-mentioned one-half of the 35 strands of wire will cross the legs of the second-named half of the wires, twisting together the crossed portions of said 40 legs for forming a plurality of substantially diamond-shaped portions radiating from 45 the common center, and bending and twisting the strands of wire for forming a cup-shaped body composed of polyhedral sections, twisting together the ends of the 50 strands of wire and curving them about a 55 stay ring.

In testimony whereof I affix my signature in presence of two witnesses.

ELY R. WESTFALL.
